GOTTHELF M. SEIDEL, OF NORTHAMPTON, MASSACHUSETTS

CARDBOARD PLANT BOX

Application filed August 20, 1929, Serial No. 387,155. Renewed September 9, 1931.

This invention relates to paper plant boxes and, among other objects, aims to provide an improved collapsible paper box intended for use by commercial florists, gardeners, and the like and to raise, transplant or propagate plants. Another aim is to provide a simple, strong, durable and inexpensive box made of a single scored sheet of suitable paper or fiber board so constructed that the blanks can be shipped in relatively small cartons or packages and can be quickly and easily assembled into boxes as they are required.

Other aims and advantages of the invention will appear in the specification, taken in connection with the illustrative embodiment of the invention shown in the accompanying drawings wherein:—

Fig. 1 is a perspective view of an assembled plant box;

Fig. 2 is a top plan view of the box shown in Fig. 1;

Fig. 3 is a sectional view through the box and showing a plant therein; and

Fig. 4 is a face view of a blank of which the preferred form of box is made.

Referring particularly to the drawings, the preferred form of box there shown is preferably made of a single sheet of suitable paper board or paper stock conveniently composed of tobacco stems or waste matter containing fertilizing material or insecticides, and it may be coated, impregnated or saturated with fertilizing elements and/or insecticides or fungicides suitable to the needs of the particular plants for which the box is intended.

Referring to the blank shown in Fig. 4, it will be noted that the single sheet of cardboard is there scored to provide side walls 1, 2, 3, 4 and 5, the walls 1 and 5 being arranged to overlap, so that the outside wall may be suitably secured to the inside wall by means of a tab 6, formed by slitting the wall 5 at 7, inserted into a straight slit 8 in the wall 1. Integral bottom wall portions 9 and 10 are connected to the side walls 4 and 5, so that one end wall is adapted to be folded inwardly across the other, the blank being suitably scored for this purpose.

At the ends of the end wall portions 9

and 10, scored tabs 11 and 12 are connected so as to be bent inwardly against the inside of the opposite side wall, as clearly shown in Fig. 3. The arrangement is such that when one end wall is folded or bent across the other and its tab inserted between the edge of the other end wall and the inside of the opposite side wall, the sides of the box are braced and the box maintains its proper shape.

In order to permit water to escape or seep through the soil in the box, both of the bottom or end walls are provided with openings 13 which are so arranged that they register with each other when these walls are folded inwardly and the box is assembled (see Figs. 2 and 3).

From the foregoing description, it will be seen that the box blanks may be very easily and economically produced by simple cutting, slitting and scoring operations. Moreover, the shape of the blank is such that a maximum number of blanks can be cut from a large sheet of cardboard without producing a great deal of waste. Furthermore, the boxes can be very easily and quickly assembled by an inexperienced workman and can be sold for a fraction of the cost of the usual small plant pots ordinarily used by florists, gardeners, plan growers and the like. Also, the boxes are sufficiently strong to withstand a great deal of abuse in shipment and small plants can be shipped great distances without material injury. The shape of the assembled boxes is such that they may be placed, one against the other, in large containers, and thereby support the side walls of each other.

A great advantage in using such fiber or pulp boxes, instead of the usual plant pots, is that plants or seedlings may be transplanted in the boxes without disturbing the plant roots and the boxes will decay sufficiently to permit the roots to penetrate them before the plants have grown to any considerable extent. Also, the decayed boxes will also fertilize the soil. The pulp or material of which the cardboard boxes are formed is of such nature that any suitable fertilizing material and/or insecticides or fungicides may be incorporated in it or applied to the surfaces.

Obviously, the present invention is not restricted to the particular embodiment thereof herein shown and described.

What I claim is:—

5 A plant cup of the class described comprising a rectangular box made of a single blank of stiff paper and having an open upper end; a double bottom wall composed of scored extensions in adjacent side walls having 10 bracing tabs inserted in the box against the other adjacent side walls; and said bottom wall portions having registering apertures which constitute a drain opening.

In testimony, that I claim the foregoing 15 as my own, I have hereto affixed my signature.

GOTTHELF M. SEIDEL.
